UNITED STATES PATENT OFFICE.

PLINY P. PIPES, OF MANSFIELD, OHIO, ASSIGNOR TO THE OHIO BRASS COMPANY,
OF MANSFIELD, OHIO, A CORPORATION OF NEW JERSEY.

RAIL-CONNECTING DEVICE.

Application filed December 23, 1926. Serial No. 156,537.

My invention relates to the method and means of electrically and mechanically connecting the adjacent ends of rails used in electric traction or in cases where the rails 5 are used for signal purposes.

The object of my invention is to provide a means which will not only mechanically connect the adjacent ends of rails and support and maintain them in relative position, 10 but to also connect them electrically and with sufficient efficiency to act as a substitute for the present type of so called rail bonds used for electrically connecting the adjacent ends of rails.

15 My invention resides in the new and novel construction, combination and relation of the parts herein described and shown in the accompanying drawing and the steps relative thereto.

20 In the accompanying drawing:—

Fig. 1 shows an end view of my invention taken on the line 1—1 of Fig. 2. In this figure one splice plate is shown in its relative position with respect to the rail and the 25 other splice plate is shown slightly removed from its final relative position so as to more clearly show the details of my invention as later described. This figure also shows the bolts for drawing the splice plates into position and maintaining them in position.

Fig. 2 shows a side view of two adjacent rail ends with a splice plate bolted into position.

In the preferred embodiment of my invention I employ as a mechanical and electrical connecting means, a splice plate, one of the usual various types found on the market, and to the contacting faces of such splice plates with the base and head of the rail I apply a 35 coating 2 and 3 respectively, of a conducting metal which is superior in conducting properties to that of steel.

The coatings 2 or 3 may consist of copper, tin, zinc or other suitable metals of higher 45 conductivity than that of steel or iron.

Zinc, I find, makes a very good coating for the reason that it is not only a protection against corrosion of the surface to which it is integrally attached or secured, but through 50 its well known electro-chemical action it will also protect a surface which it may contact with against corrosion but to which it is not integrally or molecularly attached.

The coating may be applied to the contact- 55 ing surfaces of the plate with the rail or it

may be applied to the entire surface of the plate.

In order to apply the conducting metal to the surfaces of the plate which contact with the rail, I make use of the well known Schoop process of applying coatings which is made with what is known in the industry as a metal spray gun, by means of which the metal is brought to a molten state and sprayed in very fine particles upon the surface to be coated.

Also, the conducting metal may be applied to the contacting surfaces of the plate by the electro-plating process and in this case those surfaces not to be coated with the conducting metal have applied thereto a coating of paraffin or heavy grease, etc., and which would prevent any deposition of the conducting metal upon such surfaces.

If it is desired to cover all surfaces of the plate then they can first be cleaned of scale, 75 rust, oxide, etc., and dipped in the molten metal which is to form the conducting coating.

I may employ a conducting coating upon the plate, of tin, zinc, copper or brass, but this coating should form an integral part 80 of the plate as would be the case when such coating was applied by dipping in the molten metal as in the hot galvanizing process or applying as a spray by means of a metal spray gun or by applying electro-chemically as by plating.

While a plate as described above may be used in which the conducting metal contacts with the bare surface of the base and head 90 of the rail greater efficiency may be attained by cleaning and coating those surfaces of the rail which contact with the coating metal on the plate, and this can be brought about by cleaning such surfaces of the rail and applying thereto a coating metal preferably by means of the metal spray gun. Such a coating is represented by numerals 4 and 5 on Fig. 1. The cleaning of the rail surface can be brought about by means of a portable sand blast machine.

If the entire surface of the plate 1 is covered with the conducting metal I find that the efficiency is somewhat greater than where just the contacting surfaces are coated. And the same is true if the entire surface of the rail within the length of the splice bar is coated with the conducting metal in place of just the contacting surfaces.

Also, the coating on the rail and plate need

not be of the same metals, but I prefer to have them of the same metals as this precludes electrolytic action between the coating metals.

5 It is my belief that attempts have been made to insert separate conducting means between the plate and rail and to draw the same into close contact by means of bolts, but in my invention I make the coating an integral 10 part of the plate and/or the rail. When a separate conducting member, such as sheet copper, is clamped between the plate and rail we have two contact surfaces formed by pressure, namely; between the plate and 15 copper and between the rail and copper. In my arrangement there is only one contact surface, and that is between the two conducting coatings and this surface is between the metal of higher conductivity than that of the 20 rail or plate and the contact or union of the conducting coating with the plate or rail in my arrangement is of very low resistance.

The Schoop process of applying the coating is fully described in Schoop Patent 25 1,128,058, dated February 9, 1915, and a metal spray gun is shown in detail in Morf Patent 1,100,602, dated June 16, 1914. Both the Schoop process and the metal spray gun are well known in the arts and sciences. The 30 method of rolling splice plates is well known and also the coating of articles by means of electro-plating and the application of a coating of molten tin or zinc is well known. In coating the plates the surface to be coated 35 must be well cleaned of scale, oxide, grease, etc., under any process used.

Having applied the coating to the plate and to the rail the plates are positioned upon the rail and drawn tightly into engagement with 40 the rail by means of the bolt 6 and nut 7. The coating of the plate is probably best done at the factory, but the coating of the rail can be carried out at the point of installation by means of a portable sanding outfit or a portable grinder and a metal spray gun.

Between the nuts 6 and the plates I place 50 a spring lock washer 8 which insures a constant pressure of the plates against the rail at all times and, therefore, the prepared conducting surfaces are assured of contact, as the washers may be said to automatically maintain the said contact.

By the use of my invention the fish plate 55 acts as both a splice bar and a bond, thereby combining both functions in one device and avoiding the necessity of a separate rail bond to electrically connect the rails, and by maintaining the plates in tightly bolted condition with respect to the rails an efficient joint, both 60 mechanically and electrically, is secured and maintained.

Having described my invention, I claim:

1. A rail joint comprising two alined and 65 abutting rails, splice plates disposed on opposite sides of the rail between the head and

base, a coating of metal having a higher specific conductivity than that of the rail applied to the surface of the plates and integrally united thereto and means to draw the plates into position relative to the rails and 70 the said coatings into contact with the rail surface.

2. A rail joint comprising a pair of rails having alined and abutting ends, a splice plate secured to the rails in spanning relation to the rail ends and interposed between and contacting with the head and base of the rails on each side of the rails, a coating of metal having a higher specific electrical conductivity than that of the plate secured to the 75 surface of the plate and another coating applied to the surface of the rails engaged by the plate and forming an integral union with the rail and with the plate and means passing 80 transversely through the rails and plates to 85 secure the plates and rails in relative relation and the coatings in close engagement.

3. A connecting member for two adjacent rail ends comprising a plate of ferrous metal 90 to engage and connect the two rails, a coating of metal forming an integral union with the engaging faces and having a lower specific resistance than the plate and means to secure the plate in position to electrically conduct 95 current from rail to rail.

4. A splice plate for rails comprising a plate to engage the rails, a coating of rust 100 proof metal integrally united to the surface of the plate and having a higher specific electrical conductivity than that of the plate, and means to receive holding means to secure the plate in position.

5. A combined rail splice plate and bond comprising a plate having oppositely disposed faces to engage the oppositely disposed faces of the rail head and base, a metallic coating upon the oppositely disposed faces of the plate composed of metal having a higher specific electrical conductivity than that of the plate and forming an integral 105 union of molecular character with the plate and means to receive securing means to hold the plate in position.

6. An article of manufacture for mechanically coupling and supporting and electrically connecting the adjacent ends of rails comprising a plate to be interposed between the head and the base of the rail, transverse openings through the plate to receive bolts to draw and hold the plates in position between 120 the head and base of the rail and a uniform metal coating of higher electrical conductivity than that of the plate reposing upon the surface of and forming a molecular union with the said article and adapted to engage the head and base of the rails, and bridge the joint to carry current from one rail to the 125 other.

7. A splice plate comprising a ferrous plate having surfaces to engage a rail, trans- 130

verse openings and a coating on the rail engaging faces of an adhering layer of dissimilar metal forming a molecular union with the plate.

- 5 8. The method of manufacturing a rail bond to connect two adjacent rails comprising the application to the entire contacting surface of a plate to engage the rails in overlapping relation thereto an adhering coating 10 of metal of high conductivity as compared to the plate and molecularly united to the plate and applied thereto by spraying the metal on the surface after it has been reduced to fine subdivision by heat.
- 15 9. A connecting member for two adjacent rail ends comprising a plate of ferrous metal to engage and connect the two rails, a uniform coating of metal forming an integral molecular union with the entire engaging 20 faces and having a lower specific resistance

than the plate and means to secure the plate in position to electrically conduct current from rail to rail, and yielding means between the securing means and the plates biased to move the plates toward the rails.

25 10. A rail joint comprising a pair of aligned rails, a splice plate secured to the rails in spanning relation to the rail ends and interposed between and contacting with the head and base of the rails, a layer of metal 30 integrally secured to the contacting surface of the plate and rail and having a higher specific conductivity than that of the plate and means passing transversely through the plate and rails to secure the plate and rails 35 in relative relation and the coatings in close engagement.

In testimony whereof I affix my signature.

PLINY P. PIPES.
